UNITED STATES PATENT OFFICE.

HALFORD W. PARK, OF SCARSDALE, NEW YORK, ASSIGNOR TO ROCKWOOD SPRINKLER COMPANY OF MASSACHUSETTS, OF WORCESTER, MASSACHUSETTS, A CORPORATION OF MASSACHUSETTS.

AUTOMATIC DEVICE FOR DRAINING VARIABLE-PRESSURE ALARM SYSTEMS.

Application filed December 31, 1921. Serial No. 526,427.

To all whom it may concern:

Be it known that I, HALFORD W. PARK, a citizen of the United States, residing at Scarsdale, in the county of Westchester and State of New York, have invented a new and useful Automatic Device for Draining Variable-Pressure Alarm Systems, of which the following is a specification.

This invention relates to an automatic device for controlling the supply and discharge of water under pressure for operating an alarm or the like.

The principal objects of the invention are to provide means which will insure that when the alarm valve check lifts from its seat all the water discharged through the pipe and spaces connecting the annular port of the alarm valve with the alarm actuating mechanism will be utilized for alarm purposes without waste, and to provide means which will insure that when the check closes, the water thereby left trapped in the alarm valve system will be drained forthwith leaving the alarm valve connecting pipe and spaces in their normally empty condition and thus automatically ready for further operation; to provide a construction in which, although both of the above objects are attained, no alarm will result from the uncovering of the annular port as the effect of mere water hammers transmitted to the alarm valve through the water in the system; to provide a system in which there are no moving parts except a float valve, nothing to create friction and nothing to corrode; and to provide these features in such form as to be practically applicable to a fire sprinkler system.

Further objects and advantages of the invention will appear hereinafter.

Reference is to be had to the accompanying drawings, in which—

Fig. 1 is a longitudinal central sectional view of a part of a sprinkler system showing a preferred form of this invention applied thereto, and

Fig. 2 is an end view of the retarding chamber and controlling device.

I have shown the invention as used in connection with a variable pressure alarm or check valve 10, in this instance used in connection with a water main 11 under high pressure and a stand pipe 12 to which the various sprinkler heads are connected.

When the valve 10 opens, either on account of reduction in the pressure above it, or for any other reason, water will flow as usual through a pipe 13, the end of which is connected with an annular port in the valve seat which is normally closed by the valve 10. The pipe 13 is shown as feeding through a passage or other conduit 15, in the usual way, into a retarding chamber 16. This chamber is connected by a pipe 17 with a water motor alarm device 9, located at any desired place and adapted to be operated by the flow of water from the retarding chamber to sound an alarm. The parts so far described are of the usual construction and serve the usual purposes. This invention does not need to be used with a retarding chamber, as it can serve for retarding purposes itself to prevent sounding of the alarm in case of water hammer, with modifications within the skill of those skilled in the art.

In order to discharge the water from the retarding chamber it has been customary heretofore to provide it with a constantly open drain outlet of small area which will, of course, discharge water all the time the retarding chamber is being filled and all the time that the alarm is operated. In order to secure sufficient operating pressure at the gong this drain opening has to be made small and therefore it takes a long time for the retarding chamber and connecting pipes to be drained by it after the alarm valve check 10 is closed. As stated above, this invention involves means by which all the water that flows by the valve check 10 through the pipe 13 will be delivered into the retarding chamber or the alarm motor system without waste and when the valve 10 closes again the water will immediately discharge from the retarding chamber into the atmosphere at a rapid rate and this discharge will continue until the retarding chamber and connecting pipe and spaces are empty. The rapidity with which the parts are brought back to normal condition for operation again permits the real function of the retarding chamber to be maintained by preventing water hammers, even if occurring in close succession from starting the alarm to operate.

For these purposes I can attach the device anywhere in the pipe line between the alarm

valve 10 and the water motor 9; but I have shown it as attached to the cover plate 18 of the retarding chamber which is usually located on the bottom. For that purpose I have shown the passage 15 as located in this cover plate. This also is usual, but I have applied to the cover plate a casing 19 to which is connected below it a second casing 20. In this casing 19 there is a passage 21 provided at the top with a Pitot tube 22. This is turned toward the alarm valve 10 and therefore when water flows toward the retarding chamber from the main valve some of it will be forced to flow down this tube and through the passage 21 into a pressure chamber 23 below. This exerts pressure on a body of heavy liquid, preferably mercury, 24 in the bottom of that chamber. At the bottom this chamber has a port 25 connecting with a suction chamber 26 also located in the casing 20 and, of course, also having a body of mercury in it which, when there is no pressure, will come to the level of the mercury in the pressure chamber 23. Floating in the mercury of the suction chamber is a float 27 which can be made of cast iron, weighted with lead 28, if desired, and provided with a valve 29 at the top which preferably is formed of Monel metal. Just above this valve is a valve seat having a large drain port 30 through it which also can be formed of Monel metal. This port communicates with a trap or chamber 31 in the casing 19, which in turn, communicates with a discharge pipe or port 32 near the top of the trap for discharging water from the system into the open air.

Also communicating with the top of the suction chamber 26 there is a passage 33 leading into a safety trap or chamber 34 in the casing 19. On the top of this there is a Pitot tube 35 somewhat larger than the tube 22 and with its curved end turned in the opposite direction. The passage 33 is larger than the passage 21 also but the passage in the valve seat is still larger. The bottoms of the traps 31 and 34 slope in all directions toward their openings in the bottom to allow the mercury to drain out if it flows into them.

When the clapper of the main alarm valve is shut and the alarm valve system is drained there is very little hydrostatic pressure on the surfaces of the mercury in the two chambers and what there is is nearly equal, so these surfaces are at substantially the same elevation. The float 27 therefore remains in its lowest position leaving the vent hole 30 open to the atmosphere. Whenever the valve 10 opens and the water starts to flow into the retarding chamber, the action of this flow of water unbalances the pressure in the two chambers 23 and 26 in two ways. Pressure is exerted in the chamber 23 by the head due to the velocity of water past the Pitot tube 22 and suction is created in

the chamber 26 by the flow of the water past the other Pitot tube 35. The first of these can be made sufficient to close the valve 29 but I prefer to rely on the two together. The pressure chamber 23 being closed and the suction chamber 26 being open to the atmosphere, the hydrostatic head exerted through the tube 22 will, of course, cause the mercury to rise in the latter and to fall in the former independently of the velocity head of the water. Without reference, therefore, to the Pitot tube 35, there are two forces acting to close the valve 29, first, the hydrostatic head as soon as any water is received in the retarding chamber, and second, the pressure due to the velocity head due to the water flowing through and past the tube 22. Either the difference in the pressure due to the hydrostatic head alone or the difference in pressure due to velocity alone will cause the float to rise. The float having once risen, the pressure due to hydrostatic head in the two chambers becomes balanced because there is no outlet and therefore the only pressure left to hold the valve closed is that due to the velocity of the water flowing past the tubes 22 and 35, plus the unbalanced hydrostatic head on area of the valve equal to the area of the port 30. If it were not for the Pitot tubes, therefore, or at least one of them, the float would fall back from the vent hole. It is chiefly the difference in velocity pressure due to these two tubes that holds the float on its seat while the water is flowing.

Just as soon as the water flow stops, this difference in velocity head also disappears and as the hydrostatic head on the two chambers is already equal, the mercury returns to the original equal levels in the two chambers and the valve 29 opens by gravity, coming down into the position shown in Fig. 1. Now, the water is free to drain out through the port 30 as rapidly as it went into the retarding chamber and thus the device is restored to its set condition ready to operate when the valve 10 opens again.

The vent hole receives and discharges its water into the safety trap 31 which is large enough to contain all the mercury in the pressure chamber that cannot be contained in the suction chamber when the float is up to its valve seat. The drain 32 leads from near the top of this chamber 31. This safety chamber is designed to guard against any possibility of loss of mercury through the drain pipe if the valve should not seat perfectly and if the difference in velocity head under heavy pressures should be great enough to lift the mercury over the float through the vent hole.

The safety trap or chamber 34 is provided to guard against any similar loss of mercury through this passage into the flow pipe.

There being only a very small velocity of water through these safety chambers it is impossible for any mercury to escape. The bottoms of these chambers are sloped toward their inlets at the bottom so that as soon as the pressure is relieved any mercury that might have gathered in them runs back to its proper place in the suction chamber. It is to be observed that no matter how great the velocity of water becomes due to heavy water pressures, the only amount of mercury than can be forced into either safety chamber is the amount that is left in the pressure chamber after the suction chamber is filled with mercury. After this small amount has been forced into the safety chamber any water coming into the latter from the pressure chamber will rise through the mercury and the level of the mercury cannot be raised further.

It is to be observed that while the water is flowing the force holding the float on its seat continually increases until the maximum force is obtained when the retarding chamber and the pipe to the water motor nozzle are completely filled. If there should be a slight leak around the valve 29 while the float is seated it would not affect the operation of the alarm. It is to be noted that there are no moving parts in the device except the float and nothing to present any friction or to make it possible for the parts to corrode or fail to operate. It depends solely and directly upon the laws of hydrostatics.

Although I have illustrated and described only a single form of the invention, I am aware of the fact that modifications can be made therein by any person skilled in the art without departing from the scope of the invention as expressed in the claims. Therefore, I do not wish to be limited to all the details of construction herein shown and described but what I do claim is:—

1. In a water alarm system, the combination with an alarm valve, a water motor nozzle, and a passage for conducting water from the alarm valve to a water motor nozzle when the alarm valve opens, of a drain outlet for the water in the system located between the alarm valve and the water motor nozzle and connected with said passage, a valve adapted to completely close said outlet, and means for causing the pressure due to the flow of water through the system to act on the valve to close it, whereby the valve will open as soon as the water stops flowing.

2. In a water alarm system, the combination with the main alarm valve, a water motor alarm, means for conducting water under pressure from the main to the water motor when the alarm valve opens, a drain outlet port for the water in the system, a separate passage from said means to said

port and a valve controlling the flow of water through said port, of means whereby the last named valve will tend to remain closed whenever the water flows in the direction from the alarm valve to the water motor and the valve will be forced against said seat by the pressure caused by the flow of water, and whereby it will also be held against the seat by the hydrostatic head of water in the system, said valve being arranged and adapted to recede from its seat as soon as the pressure due to the flow of water stops.

3. In an automatic alarm valve system, the combination with a main alarm valve, a water motor alarm, and a conduit controlled by the main valve for conducting water from the riser to the motor when the alarm valve opens, of a discharge port, an upwardly opening port for discharging the water from the system into said discharge port, a valve below it adapted to close the port from below, and means whereby said valve is held up in opposition to its weight against the valve seat to close it by the force of the water flowing through the system from the riser to the water motor and whereby when it becomes seated the hydrostatic head of water above it will assist in holding it to its seat, said valve having a weight sufficient to cause it to fall away from the seat whenever acted upon only by the hydrostatic head in the system.

4. In a device of the character described, the combination of a retarding chamber, a conduit for leading water thereto, a discharge port, a valve seat opening upwardly for discharging the water from said conduit into said discharge port, a chamber below the valve seat, an upwardly operating valve in said chamber having a weight sufficient to cause it to drop away from the seats when held to it by nothing but the hydrostatic head above it in said retarding chamber and system, and means whereby the flow of water along said conduit toward the retarding chamber will exert pressure below said valve to force it up against the valve seat and whereby when it has once closed, the hydrostatic head will also assist in holding it against the seat.

5. In a device of the character described, the combination with an alarm motor and a conduit for conducting water thereto, of a Pitot tube projecting into said conduit and having its curved admission end extending toward the source of pressure in the conduit, two chambers below the conduit one communicating with said tube, the other chamber having an outlet port at the top and communicating with the conduit, a valve in the second chamber adapted to rise therein and close the port, and means connecting said chambers for transmitting the pressure

due to the velocity of water past the Pitot tube to said valve to cause it to be elevated and seated.

6. In a device of the character described, the combination with a retarding chamber and a conduit for conducting water thereto, of a pair of Pitot tubes extending from said conduit and projecting into it in opposite directions, two chambers below the conduit, each communicating with one of said tubes, one of said chambers constituting a pressure chamber, the Pitot tube communicating with which has its curved admission end extending toward the source of pressure in the conduit, the other chamber having an outlet opening at the top and communicating with the other Pitot tube, a float valve in the second chamber adapted to rise therein and close the port, and a body of heavy liquid in the bottoms of the two chambers which communicate with each other.

7. In a device of the character described, the combination with a retarding chamber and a conduit for conducting water thereto, of a Pitot tube extending from said conduit and projecting into it, two chambers below the conduit, the Pitot tube communicating with one of said chambers and having its curved admission end extending toward the source of pressure in the conduit, the other chamber having an outlet opening at the top and communicating with the conduit, a valve in the second chamber adapted to rise therein and close the port, and means connecting said chambers for transmitting the pressure due to the velocity of water past the Pitot tube to said valve to cause it to be seated, said means comprising an open communication between the two chambers, and a body of mercury in the bottoms of said chambers, on which mercury in the second chamber said valve floats.

8. In a device of the character described, the combination with a retarding chamber and a conduit for conducting water thereto, of a pair of Pitot tubes extending from said conduit and projecting into it in opposite directions, two communicating chambers below the conduit, each communicating with one of said tubes, and having a body of heavy liquid therein, one of said chambers constituting a pressure chamber the Pitot tube communicating with which has its curved admission end extending toward the retarding chamber, the other chamber having an outlet opening at the top and also communicating with the other Pitot tube, a valve in the second chamber floating on the liquid therein so as to be adapted to

rise therein and close the port, whereby the pressure due to the velocity of water past the Pitot tube at the top of the pressure chamber will be transmitted through the heavy liquid to said valve to cause it to be seated, and a safety trap above said port for retaining any of said heavy liquid that flows into it and discharging it back into the second chamber.

9. In a device of the character described, the combination with a retarding chamber and a conduit for conducting water thereto, of a pair of Pitot tubes extending from said conduit and projecting into it in opposite directions, two chambers below the conduit each communicating with one of said tubes, and communicating with each other at the bottom, one of said chambers constituting a pressure chamber and the other having an outlet port, a body of mercury in the two chambers, a valve in the second chamber floating on the mercury and adapted to rise therewith and close the port, and a safety trap or chamber connecting the second chamber with the second Pitot tube for receiving any mercury that may rise above the second chamber and feeding it back by gravity into said second chamber when the pressure is removed.

10. In a device of the character described, the combination with a conduit of a pair of chambers below the conduit communicating with each other at the bottom, one of said chambers constituting a pressure chamber and the other having an outlet port, a body of mercury in the two chambers, a valve in the second chamber floating on the mercury and adapted to rise therewith and close the port, and a safety trap or chamber connecting the second chamber for receiving any mercury that may rise above the second chamber and feeding it back by gravity into said second chamber when the pressure is removed.

11. In an alarm system, the combination with an alarm adapted to be operated by the flow of water thereto, means for conducting water to the alarm comprising a conduit, an outlet connected with said conduit, a valve for closing said conduit, means for operating the valve, means whereby suction is produced just beyond the orifice when water flows through the conduit to the alarm, and means whereby the suction is transmitted to the valve to close and hold it closed while the water is flowing.

In testimony whereof I have hereunto affixed my signature.

HALFORD W. PARK.
